his Atty.

UNITED STATES PATENT OFFICE.

GEORGE W. SMILLIE, OF NEWARK, NEW JERSEY, ASSIGNOR TO THE SMILLIE COUPLER AND MANUFACTURING COMPANY, OF NEW JERSEY.

CAR-COUPLING.

SPECIFICATION forming part of Letters Patent No. 451,883, dated May 5, 1891.

Application filed January 21, 1891. Serial No. 378,532. (No model.)

To all whom it may concern:

Be it known that I, GEORGE W. SMILLIE, a citizen of the United States, and a resident of Newark, in the county of Essex and State of New Jersey, have invented new and useful Improvements in Car-Couplers, of which the following, taken in connection with the drawings herewith accompanying, is a specification.

10 My invention relates to that class of car-couplers known as the "vertical-plane" couplers, and usually provided with a hinged jaw or hook for engaging and coupling with a corresponding part of another or second coupler 15 and with a coupling-pin or other device for adjustably locking the said hinged jaw or hook in a locked position with its engaging coupler; and my invention consists in the construction of the said hinged jaw or hook and 20 in the combination therewith of a hinged plate or apron for supporting the pin or device for locking the said hinged jaw or hook in a manner as will hereinafter be set forth in detail, and pointed out in the claims.

25 The main object of my invention is to provide a means for adjustably supporting the coupling-pin or other device for locking the locking jaw or hook in a raised position from engagement with such locking jaw or 30 hook or part thereof that is located and adapted to operate at or near the center of the draw-head in order to prevent the necessity of reducing or cutting away the shell or body of the draw-head and thereby impair its strength 35 and durability. Hence my invention.

Referring to the drawings, Figure 1 represents two of my improved couplers in engagement; Fig. 2, a horizontal sectional view of the same; and Fig. 3, a single coupler, showing the locking jaw or hook open or in position as when uncoupled.

In the drawings, A represents the draw-bar, and B the draw-head, provided with two arms or extensions b b, projecting from the front 45 face thereof, forming a recess for the admission of the engaging jaw or hook in a manner as shown.

C represents the coupling jaw or hook hinged to one of the said arms or extensions 50 b, and provided with an arm c extending at right angles, or nearly so, therefrom into a

suitable opening in the draw-head. Said arm c is adapted to be engaged on its forward side in order to hold the jaw or hook C in a locked position with an engaging coupler by a coupling-pin D, which latter is supported and adapted to operate in a vertically-arranged opening a in the draw-head. The said arm c is provided on its rear side thereof with a hook or projection c', which is adapted to engage 60 with a counterpart projection a' in the wall of the draw-head when the locking jaw or hook C is coupled or in engagement with another coupler, as shown in Fig. 2, in order to relieve the strain on the pivot-pin c², and also 65 to prevent the locking jaw or hook from being pulled from its position in the draw-head in case of the loss or breakage of its pivot-pin c², said hook or projection being held in such engagement with its counterpart projection 70 by means of the coupling-pin D, as will be readily understood. By this method of construction the strain upon the coupling-hook C is divided between the pivot-pin c², the coupling-pin D, and the said projection a', in 75 lieu of being directly upon the pivot-pin in the usual manner, and thereby greatly increasing the strength of the coupler. When the coupling jaw or hook C is thrown open to uncouple or disengage with a connecting-coupler, the end of its arm c engages with a projection a³ in the draw-head to limit its outward throw, as will be readily understood.

E represents a horizontally-arranged plate or apron adapted to support the coupling-pin 85 D when raised from engagement with the arm or extension c of the locking jaw or hook, and is pivotally connected at or near one end to the arm or extension c near its pivot-point, and at its opposite free end extends into the 90 opening a² in the draw-bar, said opening being of suitable dimensions to hold the said free end of the plate or apron E in a stationary, or nearly so, position, and allow a slight lateral movement or play of the same for its 95 proper operation, as will be readily understood hereinafter. When the coupling-pin D is raised from engagement with the arm c of the locking hook or jaw and the latter is opened, as shown in Fig. 3, the plate E is 100 moved or carried forward, by reason of its connection with the arm c of the locking-jaw,

a sufficient distance to bring the cavity or seat *e* therein to a position immediately beneath the end of the coupling-pin *D* for the support of the latter. When the locking jaw or hook 5 is closed, as shown in Fig. 2, by reason of its engagement with an engaging coupler or otherwise, the plate or apron *E* is moved back from its position under the coupling-pin to allow the latter to drop into position to en-

10 gage with the arm or extension *c* and hold the locking jaw or hook in its locked position.

Having thus set forth my invention, I do not wish to be understood as claiming, broadly, a means located within the draw-head for sup-

15 porting the coupling-pin in a raised position from engagement with the locking jaw or hook or a part thereof; but

What I claim as new, and desire to secure by Letters Patent of the United States, is—

20 1. In a car-coupler, the combination, with the draw-head, of a hinged locking jaw or hook, a supporting plate or apron pivotally connected at one end to the said locking jaw or hook or a part thereof, and a coupling-pin,

25 substantially as described, and for the purpose set forth.

2. In a car-coupler, the combination, with

the draw-head, of a hinged locking jaw or hook, a horizontally arranged supporting plate or apron pivotally connected at one end 30 to the said locking jaw or hook or a part thereof and at its opposite free end projects and is loosely supported in an opening in the draw-bar, and a device for engaging said locking jaw or hook, substantially as de- 35 scribed, and for the purpose set forth.

3. In a car-coupler, the combination, with the draw-head, of a hinged locking jaw or hook provided at or near its inner end with a projection adapted to engage with a counterpart projection with which the draw-head is provided, a plate or apron adapted for the support of the coupling-pin or other locking device pivotally connected with the said locking jaw or hook and operated thereby, and a 40 device for engaging with the said locking jaw or hook to adjustably lock the same, substantially as described, and for the purpose set forth.

GEO. W. SMILLIE.
